UNITED STATES PATENT OFFICE

2,676,422

AERATOR PUMP FOR SHOES

Arthur C. Crawford, Rodeo, Calif.

Application August 13, 1951, Serial No. 241,558

2 Claims. (Cl. 36-3)

1

The present invention relates to improvements in an aerator pump for shoes particularly intended to automatically aerate the inside of foot wear, such as boots, waders, shoes and the like, while the foot wear is being used in walking or other exercises.

When foot wear is used in walking or other exercises there is a continuous reciprocating movement between the rear portion of the foot and the corresponding portion of the foot wear, the heel portion of the foot being lifted away from the heel portion of the foot wear at the initiation of every step, and coming down firmly upon the foot wear at the end of each step.

In the present invention it is proposed to utilize this reciprocating motion of the heel section with respect to the foot wear for actuating a pump interposed between the bottom of the foot and the heel section of the foot wear, the pump being intended to continuously remove foul air from the contact area and to allow fresh air to enter.

In carrying out this idea, it is proposed to provide a flat pump chamber adapted for placing in the bottom of the foot wear and resilient means inside the pump chamber adapted to expand the latter as the foot is lifted and to collapse under the weight of the descending foot, the pump chamber being provided with suitable intake and exhaust ports and valves for pumping action.

It is further proposed to provide for a conduit connecting the exhaust ports with the upper end of the foot wear so as to allow the pump gas or foul air to be discharged over the upper edge while fresh air is allowed to enter from all around the foot wear to replace the foul air.

It is further proposed to provide an extension sheet for the pump chamber extending clear to the front end of the foot wear so as to retain the pump chamber in the rear portion of the latter.

It is a further feature of the present invention to arrange the pump chamber somewhat narrower than the width of the foot wear so that the side walls of the pump chamber are spaced from the side walls of the foot wear and may be utilized for accommodating the intake and exhaust ports.

And finally, it is proposed to use for the resilient expansion means a corrugated sheet of sponge rubber or similar material, the sheet being arranged to stop short of the side edges of the pump chamber so as to provide side passages, and with the corrugations disposed transversely

2

to establish communication between the side passages and to allow of free circulation of air through the chamber.

Further objects and advantages of my invention will appear as the specification proceeds, and the novel features of my invention will be fully defined in the claims attached hereto.

The preferred form of my invention is illustrated in the accompanying drawing, in which

- 10 Figure 1 shows a side view of a boot equipped with my aerator pump, portions being shown in section,
 Figure 2, a horizontal section taken along line 2-2 of Figure 1,
 15 Figure 3, a transverse section taken along line 3-3 of Figure 2, and
 Figure 4 a transverse section taken along line 4-4 of Figure 2.

While I have shown only the preferred form 20 of my invention, I wish to have it understood that various changes and modifications may be made within the scope of the claims attached hereto without departing from the spirit of the invention.

25 Referring to the drawing in detail, the boot 1 may be of any conventional type, comprising a sole 2, a heel 3, and an upper 4.

My pump 5 is adapted for insertion into the boot over the heel section and consists primarily of a flat pump chamber 6 made of flexible material and having flat top and bottom walls 7 and 8 and vertical side walls 9.

The width of the pump chamber is somewhat less than the inside width of the boot so as to leave side passages 10 on opposite sides of the chamber, and the length of the latter is such that it extends over the heel and the instep of the boot as shown. In order to insure proper positioning of the pump chamber in the rear portion of the boot, I provide an extension sheet 11 which may be formed integral with the top or the bottom wall of the chamber and which is commensurate with the inside dimensions of the forward portion of the boot.

45 The pump chamber is provided with a resilient medium tending to expand the same. In the form shown, this resilient medium comprises a corrugated, rather heavy sheet 12 of sponge rubber or similar material, the sheet being made of a width slightly less than the inside width of the pump chamber so as to leave side passages 13 along the side walls of the chamber, and the corrugations being arranged transversely to form numerous communications between the side passages for the free circulation of air. The top and

bottom faces of the corrugations are preferably glued to the top and bottom members of the chamber respectively.

A number of intake ports 14 are arranged in the side walls of the pump chamber and are provided with suitable intake valves 15 which open when suction is created in the chamber, and close when the chamber is compressed.

A number of outlet ports 16 are also arranged in one or both side walls of the chamber, and tubes 17 communicating with the outlet ports may be made to lead to a manifold 18 which again connects with a discharge tube 19 leading to the top of the boot. The latter tube may be guided along the upper of the boot, as shown, preferably through the cavity behind the ankle bone, the location of which is indicated at 20.

The tube 19 is provided with a suitable check valve or exhaust valve indicated at 21 and may discharge into the atmosphere through the open end thereof as at 22, or through a lateral check valve 23 if it is desired to keep the upper end closed. It may be secured upon the inner face of the side wall of the boot by adhesive straps 24.

The entire pump may be made as a separate unitary structure adapted for insertion into and removal from the boot, or may be built into the latter as a permanent fixture.

In operation, as the wearer of the boot lifts the rear portion of the foot in initiating a forward step, the corrugated sheet of sponge rubber lifts the upper wall of the pump chamber and causes the latter to expand with the result that air from all around the foot is sucked into the chamber through the intake ports 14. This air is free to circulate through the entire chamber due to the arrangement of the side passages 13 and the transverse channels formed by the corrugations. As the wearer sets his foot down upon completion of the forward step, the chamber is compressed, and the air present is forced out through the outlet ports 16, the manifold 18, the exhaust valve 21 and the tube 19 for discharge into the atmosphere. While air is sucked into the pump chamber from the lower portion of the boot, fresh air is drawn in from all around the leg to replenish the supply.

I claim:

1. A pump chamber for a shoe of the character described, comprising a flat case made of flexible material and having top and bottom walls and a confining wall around the sides and the rear thereof, the case being dimensioned to leave a free passage around the confining wall when fitted into a shoe and the latter wall having valved intake ports communicating directly with said passage throughout the length of the wall and having an outlet port therein and a conduit directly connecting therewith, and resilient means inside the case to resiliently space the top and

bottom walls, the resilient means being operable by foot pressure to yield for driving air confined in the case through the conduit, and being adapted upon release of the foot pressure to draw air from all around the case into the latter for discharge by subsequently applied pressure.

2. A pump chamber for a shoe of the character described, comprising a flat case made of flexible material and having top and bottom walls and a confining wall around the sides and the rear thereof, the case being dimensioned to leave a free passage around the confining wall when fitted into a shoe and the latter wall having valved intake ports communicating directly with said passage throughout the length of the wall and having an outlet port therein and a conduit directly connecting therewith, and resilient means inside the case to resiliently space the top and bottom walls, the resilient means being operable by foot pressure to yield for driving air confined in the case through the conduit, and being adapted upon release of the foot pressure to draw air from all around the case into the latter for discharge by subsequently applied pressure, and the resilient means comprising a sheet of corrugated rubber having its corrugations disposed transversely with respect to the case and stopping short of the sides thereof to allow of free communication of any of the intake ports with the outlet port.
